UNITED STATES PATENT OFFICE.

EMMA F. HOLLAND, OF NEW YORK, N. Y.

CUSPIDOR.

SPECIFICATION forming part of Letters Patent No. 766,252, dated August 2, 1904.

Application filed March 19, 1904. Serial No. 198,894. (No model.)

To all whom it may concern:

Be it known that I, EMMA F. HOLLAND, a citizen of the United States, residing at New York, in the county of New York and State of New York, have invented new and useful Improvements in Cuspidors, of which the following is a specification.

My invention relates to new and useful improvements in cuspidors of the type which are intended for individual use and which are capable of being carried on the person and which may be used in public without attracting attention, said device being attachable to and susceptible of being concealed in the folds of a handkerchief or sheet of textile fabric and readily removed therefrom and the parts separated one from the other to facilitate the thorough and effective cleansing and, if desired, disinfection of said parts.

The object of my invention is to provide a simple device of small size capable of being carried on the person and having a containing-chamber for saliva or expectorated fluid matter, said chamber having a hinged closure normally secured by a catch which may be released at the time of use to enable the closure to open and expose the chamber, the said device being preferably designed to be contained in a pocket formed by gathering or otherwise arranging a flexible fabric, such as the ordinary handkerchief, whereby the device is practically concealed in said folds and is capable of being used upon any occasion without the device being observed by any one but the user.

My invention consists, essentially, of a portable cuspidor which comprises a receiving-chamber the upper portion of which is separably connected to allow the contents of the chamber to be removed and to facilitate the cleansing of the chamber, a hinged closure for said upper portion, a fabric sheet or handkerchief having a pocket to receive and retain said cuspidor, and means whereby the cuspidor when contained in said pocket of the handkerchief is capable of being suspended from the person, said handkerchief serving to conceal the device and yet allow the latter to be used without removing it therefrom.

My invention also consists of the parts and

the constructions and combinations of parts, 50 which I will hereinafter describe and claim.

In the accompanying drawings, forming part of this specification, and in which similar letters of reference indicate like parts, Figure 1 is a perspective view showing my 55 device applied to a handkerchief. Fig. 2 is a perspective view of the cuspidor detached. Fig. 3 is a sectional view of Fig. 2. Fig. 4 is a modification to be referred to.

In constructing my device I have kept in 60 view the production of a cuspidor or receptacle of a highly attractive character and which has but a minimum of weight and which is of such reduced dimensions that it is readily contained in a pocket formed by gathering 65 the folds of a handkerchief or like sheet of textile fabric, whereby the device is thoroughly concealed when not in use and is unseen by all except the user when the device is actually put into operation, the manipulation of the device simply following to all appearances the application of the handkerchief to the face, as in the act of wiping the mouth, and without drawing particular attention to the device or to the act itself. 75

In carrying out my invention I may use any one of the several forms shown, or I may employ the salient features in other relations. I prefer, however, to make the device of separable parts and of such design that the fluid 80 matter once delivered into the vessel will be retained therein against accidental spilling and soiling of the hands or toilet. The material of which the device is made is also unimportant; but to secure lightness and at the 85 same time strength and durability I prefer to use thin metal—aluminium or an alloy thereof, celluloid, vulcanite, or like material. In the more expensive forms the precious metals, as gold and silver, may enter into the general construction. 90

Referring now to the form of device shown in Figs. 1, 2, and 3, A represents the receiver or body of the cuspidor, which is shown as of circular form, although other forms may be 95 considered as within the scope of the invention. This receiver or body is also shown as of substantially bowl shape with an annular

rim portion *a* and a dished or concaved bottom *a'*. This body portion forms the reservoir for the fluid expectoration, and to enable it to be readily detached for emptying and for the purpose of cleaning I prefer to form around its upper end or rim, preferably around the inside thereof, suitable screw-threads *b*. This body portion is designed to screw into engagement with an externally-threaded rim or band *B*, the joint between the two being made liquid-tight by means of a gasket or other well-known packing, said rim or band having a hinged closure or cover *C*, which is preferably spring-actuated, so that when it is released, as by pressure upon any well-known and approved form of spring-catch at *c*, the cover will spring open and expose the interior of the body portion and allow the expectorated matter to be delivered thereto.

Secured to the inside of the rim portion is a funnel-shaped piece *D*, with its bottom terminating above the bottom of the body portion and with walls so inclined that the opening at the bottom or smaller end is disposed at one side of the center of the vertical axis of the body and is directed substantially toward the side wall of the body portion *A* of the device. This funnel-shaped piece *D* receives the fluid matter and conducts the same into the receiver or vessel *A*, and it also serves as a trap to prevent the spilling of the contents when the device is inverted, thereby avoiding the accidental escape of the contents even when the device is carelessly handled.

The device described, which is small and whose diameter may not exceed two or three inches, more or less, is designed to be carried in a handkerchief *E* and to be so concealed therein so that it may be used even in public without being seen and without attention being directed to the user. To accommodate the cuspidor, I form a pocket *F* in the handkerchief or other piece of textile fabric of such capacity as to contain the said device.

A simple method of forming the pocket in the center of the handkerchief is to secure to the latter suitable loops or rings *d*, through which a band or cord *e*, preferably elastic, is passed and drawn to gather the fabric into folds and to form the mouth of the pocket, which mouth may be of less diameter than the pocket itself and also less than the diameter of the device it is to contain; but the cord or band *e* being elastic the mouth of the pocket is readily enlarged by pressure to permit the device to be introduced and removed at pleasure. If desired, the well-known draw-string may be substituted for the elastic cord or band without departing from the scope of the invention.

When the cuspidor is in place in the pocket of the handkerchief, it is to all intents and

purposes concealed from view, and the unsecured portions of the handkerchief fall in graceful folds about the exterior of the pocket, so as to shut out from view all unnatural or unusual appearances, and when the cuspidor is to be used the handkerchief is lifted to the face in a natural manner without exposing the cuspidor, and a pressure upon the catch *c* releases the spring-actuated cover or lid *C*, which immediately flies open, allowing the fluid contents of the mouth to be deposited directly into the funnel-shaped member *D* and finally into the bowl or vessel *A* in an unnoticeable manner. To suspend the handkerchief and the contained cuspidor from the person in a graceful and convenient manner, I may attach to the rim or band portion *B* of the device suitable chains *g*, with rings *h* or equivalent means for detachably engaging rings or eyes on the rim portion of the device or for attaching to the loops or rings secured around the mouth of the handkerchief-pocket.

Instead of making the body or bowl of the cuspidor of metal or other hard and substantially inflexible material I may make it in the form of a bag *G*, as shown in Fig. 4, said bag being composed of suitable waterproof or liquid-resisting material, as rubber, the upper end or rim portion *H* of which may be vulcanized or made hard and internally threaded to receive the externally-threaded rim, with its conical trap, closure, &c., as previously described, or, if desired, the rim of the bag may simply hold to the rim by frictional contact, although I prefer the threaded connection before alluded to. When using the flexible bag *G*, the capacity of the cuspidor is very much increased, and this bag is deposited into the pocket of the handkerchief and is used in the same manner and for the same purposes as before described for the metal body portion. In both instances the lower section of the device is the receiver for the expectorated matter, and it is detachably secured for emptying and for cleaning, as before explained.

While I have described the devices as containable in the pocket of a handkerchief, it will be understood that any flexible sheet or piece of fabric, or a fabric pocket of any character to contain and conceal the cuspidor is within the scope of my invention.

Having thus described my invention, what I claim as new, and desire to secure by Letters Patent, is—

1. The combination with a cuspidor of the character described, of a sheet or piece of normally flat fabric having a series of guides fixed thereto and circumscribing substantially a minor portion of its center, a flexible member passed through said guides thereby gathering the said central portion of the fabric to form a pocket and allowing the remaining or major portion of the fabric to fall

in loose folds about the pocket to conceal the latter, said pocket adapted to conceal the cuspidor.

2. The combination with a cuspidor of the character described, of a sheet or piece of normally flat fabric having an annular series of loops fixed thereto and circumscribing substantially a minor portion of its center, an elastic cord passed through said loops thereby drawing the same toward each other to form a pocket of said central portion, said elastic cord allowing the mouth of the pocket to be expanded to insert the cuspidor therein and to remove the cuspidor therefrom, and said fabric having the portion surrounding the pocket depending in loose folds to form a curtain therefor, and means attached to the cuspidor for suspending the latter, while in the pocket, from the person.
3. In a cuspidor the combination with a bowl-shaped receiver or reservoir having internal threads, of a top section detachably secured to the receiver and consisting of an

externally-threaded annular rim and a funnel-shaped portion permanently secured to the inside thereof and removable therewith, and extending into said receiver, a cover hinged to the top section, and an outer covering of flexible material having a pocket to contain said cuspidor said pocket having an expansible and contractible mouth and being located at the center of the flexible material so as to allow the portions of the fabric between the pocket and outer edges to hang in loose folds about the pocket to thereby form a curtain to conceal the cuspidor said cuspidor when concealed within the pocket having its cover to open up through the pocket-entrance.

In testimony whereof I have hereunto set my hand in presence of two subscribing witnesses.
